[57] CLAIM

The ornamental design for the pencil holder, as shown and described.

DESCRIPTION

FIG. 1 is a perspective view of the pencil holder showing my new design;

FIG. 2 is a right side elevational view, the left side being a mirror image thereof;

FIG. 3 is a rear elevational view;

FIG. 4 is a front elevational view;

FIG. 5 is a top plan view; and

FIG. 6 is a bottom plan view thereof.

The pencils depicted by means of broken lines in FIG. 1 are for illustrative purposes only and form no part of the claimed design.

FIG. 1

FIG. 2

FIG. 3

FIG. 4

FIG. 5

FIG. 6
